VALVED DROP FORMING STOPPER WITH REMOVABLE
AIR AND LIQUID ORIFICE PLUGS

Filed Dec. 13, 1946

Fig. 1.

UNITED STATES PATENT OFFICE

2,623,662

VALVED DROP FORMING STOPPER WITH
REMOVABLE AIR AND LIQUID ORIFICE
PLUGS

Vojtěch Balcar, Prague-Smichov, Czechoslovakia

Application December 13, 1946, Serial No. 716,058

1 Claim. (Cl. 222—422)

1

The present invention relates to closure devices for bottles and the like containing a liquid and which are designed to permit the liquid to be dispensed in drops, and is an improvement upon the closure device described in my co-pending application, Serial No. 716,057 filed December 13, 1946, now U. S. Patent No. 2,605,938.

Drop type dispensing closures must be reliable in operation. When the bottle is tilted to a dispensing position, it is important that the liquid be discharged uniformly in drop form without having to shake the bottle. It is also important that all the liquid flow into the liquid discharge passage and that none flow into the air inlet passage. Otherwise, air cannot flow into the bottle in the uniform manner which is essential to satisfactory uniform discharge of the liquid. Another important characteristic of the closure is that it be able to cut off the flow accurately after the desired number of drops have been dispensed.

A preferred embodiment of the invention which makes these desirable characteristics possible is shown in the accompanying drawings wherein Fig. 1 is a vertical central section of the improved closure taken on line 1—1 of Fig. 2 and Fig. 2 is a top plan with a part broken away to show a desired detail.

With reference now to the drawing, the closure member 1 at its lower end is seen to be provided with a threaded cap portion 1a adapted to be screwed upon the neck of the bottle (not shown) containing the liquid to be dispensed. The upper end of the closure body is provided with a transverse tapered open-ended bore 2 extending therethrough and spaced air inlet and liquid outlet bores or passages 3, 4, respectively extending from spaced points in the bore to the inner surface of the closure. Bore 3 is provided with a removable orifice plug 5 for air with orifice 5a and bore 4 is provided with a removable orifice plug 6, it being noted that the orifice 6a therein is conical and enlarges in the direction of liquid discharge therethrough to ensure proper flow.

By making the orifice plugs 5 and 6 removable it becomes possible to substitute other plugs having differently sized orifices and thus alter the discharge characteristics of the closure. Thus the closure bodies may be standardized to the end that the same closure body may be used with different plugs which is more economical than having to manufacture a completely different closure for each characteristic desired.

Positioned in the tapered bore 2 is a complementary tapered rotatable plug 7 having a substantially axial bore 8 defining a liquid outlet

2

passage extending inwardly from the discharge end, and a branch transverse bore 9 connecting the bore 8 with the bore 4 when bores 9 and 4 are in alignment in one position of rotation of the plug 7. Another substantially axial bore 10 at the opposite end of plug 7 defines an air inlet passage extending inwardly from such end and a branch transverse bore 11 connects bore 10 with the air inlet bore 3 in the closure body when bores 11 and 3 are in alignment, this latter condition prevailing whenever the bores 9, 4 are in alignment.

The inner ends of the axial bores 8 and 10 are closed to render the same non-communicating and the inner end of bore 10 extends beyond the junction of bore 11 therewith by an amount greater than the diameter of bore 11 to provide an air trap 10a. Should any liquid get into the air passage, bores 4 and 11, it will go into the trap 10a compressing the air therein. However, discharge of liquid from the bottle lowers the pressure to a level less than that in trap 10a with the result that the liquid is forced out of the trap back into the bottle.

The air inlet end of plug 7 is provided with an enlarged portion 12 for easier turning by the fingers and a threaded counterbore 13 therein communicating with bore 10 serves to receive a threaded plug 14 having a longitudinal bore 15 therethrough. The inner end 14a of plug 14 is tapered to match the taper 16 at the inner end of bore 13 and hence as the plug 14 is screwed in or out, the flow of air inward through bore 15 and liquid outward from bore 8 can be correspondingly regulated. Complete air cut-off is obtained by screwing plug 14 inwardly until the mouth of the bore 15 seats against the tapered surface 16 or by rotating plug 7 until the bores 9 and 11 are no longer in registration with bores 4 and 3, respectively.

As seen in Fig. 2, plug 7 is releasably retained in the tapered bore 2 of the closure body by means of a retaining ball 17 which seats in a transverse peripheral groove 18 in the plug, the ball being spring loaded into its seating position by one end of a compression spring 19 which is positioned in a bore 20 in the closure body arranged transverse to the plug axis. The opposite end of the compression spring is retained by a screw plug 21 in bore 20.

Having now described my invention and illustrated a practical embodiment thereof, I claim:

A dropper closure for bottles comprising a body portion having a transverse tapered open ended bore extending therethrough and spaced air in-

let and liquid outlet passages extending from spaced points in said bore to the inner surface of the closure, a tapered rotatable plug seated in said bore having a substantially axial bore defining a liquid outlet passage extending inwardly from one end thereof and a branch passage connecting the outlet passage to the liquid outlet passage in the body portion in one position of rotation of the plug, said plug having a substantially axial bore defining an air inlet passage extending inwardly from the opposite end thereof and a branch bore extending from the same to the surface of the plug to communicate with the air inlet passage through the body portion in the aforesaid position of rotation of the plug, 15 the inner ends of said axial bores being closed to render the same non-communicating, the inner end of the axial bore defining said air inlet passage extending beyond the junction of the branch bore therewith a distance greater than the diameter of the branch bore, an adjustable valve in the bore defining the air inlet passage for regulating the rate at which air is passed therethrough, and removable orifice plugs mounted

in said air inlet and liquid outlet passages at the inner surface of the closure, the orifice in the orifice plug in the liquid outlet passage being conical and expanding in the direction of liquid flow therethrough.
